UNITED STATES PATENT OFFICE.

WILLIAM HOOKER ATWOOD, OF NEW HAVEN, CONNECTICUT, ASSIGNOR TO
ELECTRIC VEHICLE COMPANY, OF JERSEY CITY, NEW JERSEY, A COR-
PORATION OF NEW JERSEY.

DESIGN FOR AN AUTOMOBILE-BODY.

No. 38,486.

Specification for Design.

Patented March 19, 1907.

Application filed November 27, 1905. Serial No. 289,374. Term of patent 14 years.

To all whom it may concern:

Be it known that I, WILLIAM HOOKER ATWOOD, a citizen of the United States, residing in the city and county of New Haven, State of Connecticut, have invented a new, original, and ornamental Design for an Automobile-Body, reference being had to the accompanying drawings, in which the figure is a side elevation, partly in perspective, of my newly-designed automobile-body.

What I claim is—
The ornamental design for an automobile-body as shown.

WM. HOOKER ATWOOD.

In presence of—
JOHN MILLIKEN,
J. J. GAFFNEY.
